UNITED STATES PATENT OFFICE.

STANLEY MACOMBER, OF MASSILLON, OHIO.

FIREPROOF CONSTRUCTION AND CLIP FOR USE THEREIN.

Application filed December 21, 1925. Serial No. 76,631.

My invention relates to fire-proof floor constructions and also to means utilized for supporting and securing the wood-floor nailing strips which are mounted upon the main 5 metallic floor support and are spaced somewhat above the upper surface of the latter. The invention more particularly relates to a screed clip for mounting and securing said nailing strips. Other improvements and certain details of construction 10 will appear more fully in the following description illustrated by the accompanying drawings.

The annexed drawings and the following 15 description set forth in detail certain means embodying my invention, such means constituting, however, only a few of the several forms in which the principle of the invention may be embodied.

20 In said annexed drawings:

Figure 1 is a plan view of a fragmentary portion of the main metallic support forming part of the fire-proof floor construction, the usual expanded metal utilized therewith, and my improved clip for supporting and securing the nailing strips.

Figure 2 is a vertical section, taken longitudinally of the metallic floor support or joist and in the plane indicated by the line 25 II-II, Figure 1;

Figure 3 is a vertical, transverse section, taken in the plane indicated by the line III-III, Figure 1;

Figure 4 is a view similar to Figure 1 in which the strip-holding clip is turned 90° from the position shown in Figure 1, thus illustrating the application of the improved clip to a situation where it is desired that the floor shall run in the direction opposite 40 to that in which it would run if laid upon the base shown in Figure 1;

Figure 5 is a view similar to Figures 1 and 4, wherein the clip is turned 45°, thus illustrating the adaptation thereof to a situation wherein it is desired that the flooring 45 shall run diagonally;

Figure 6 is a view similar to Figure 2, after the concrete has been poured and the flooring has been laid;

50 Figure 7 is a view similar to Figure 1, but showing modified means for fastening the strip supporting clip to the expanded metal;

55 Figure 8 is a vertical section taken longitudinally of the supporting joist and in

the plane indicated by the line VIII-VIII, Figure 7;

Figure 9 is a vertical, transverse section, taken in the plane indicated by the line IX-IX, Figure 7;

Figure 10 is a view similar to Figure 8, after the floor has been completed; and

Figure 11 is a perspective view of my new and improved strip-holding clip.

Referring particularly to the annexed drawings in which the same parts are indicated by the same several ordinals in the respective views, I indicate by the ordinal 1 any conventional form of main support for a reinforced fire-proof floor construction; 70 by the ordinal 2 the usual expanded metal mounted upon and secured to the main support 1; by the ordinal 3 my new and improved clip, a stamped article, which is secured to and above the support 1 and expanded metal 2 and is provided with means for supporting and holding the nailing strips 4 above the expanded metal 2 and spaced therefrom such a distance as to bring the top of such strips 4 substantially flush 80 with the top of the concrete 6 which is poured over and around the metal 2 and in and around the clips 3. These strips 4 are utilized as anchors for nails 19 or other suitable securing means driven through and holding the wood floor 5.

The usual means for securing the strip-supporting clips have been wire ties 7 such as illustrated in Figures 7, 8 and 9. My improved clip is designed to provide for the use of the ties 7 or for the use of a new and improved holding member 9, illustrated in Figures 1, 2, 3 and 6, if a type of main metallic support or joist is utilized allowing for the use of such holding member 9. The 95 necessary type of joist to allow for the use of such a member 9 must be provided with two spaced members, such as illustrated by the bars 8 forming the upper chord of the joist or main support 1 which I show in the 100 accompanying drawings. This joist upper chord comprised of the spaced bars 8 is a part of a structural unit forming the subject-matter of various other patent applications filed by me. The holding member 105 is simply a wooden wedge of the approximate shape plainly shown in Figures 3 and 6, and of a width greater than the mesh of the expanded metal 2. This resilient wedge 9 when driven downwardly, simply 110

by the stroke of a hammer, through the mesh of the expanded metal 2 and between the bars 8, will become securely fixed to the latter so as securely to retain the expanded metal 2 and, if means are provided in the clip 3 for receiving the wedge 9 and allowing the same to be driven therethrough so as to become fixed therein, then this wedge 9 will serve also to retain the clip 3 in position upon the expanded metal 2 and the joist 1. I provide such means in the clip 3 through the medium of a longitudinal slot 11 formed in the base 10 of the clip. For the purpose of allowing the clip to be fastened in various relatively angular positions to provide for the laying of the flooring 5 in various directions, I provide a plurality of longitudinal slots 11 in the base 10 of the clip 3, each slot comprising two inwardly tapering end portions and a central portion 12 which is a common center hole for all of the slots, the several slots 11 being relatively angularly disposed, as plainly shown in Figure 11. This construction of a plurality of slots 11 affords the adjustability of the clip and hence of the laying of the floor, plainly shown in Figures 1, 4 and 5.

The detail construction of the rest of the clip 3 comprises relatively right-angular side members 15 struck up from the blank from which the clip is stamped, these side members 15 being perforated to form the openings 14, thus affording extensions 13 of the base 10, serving both to allow for the flowing of the concrete in and through and around the clip 3 and affording the members 13 to which the ties 7 can be secured, if the clip 3 is secured to the expanded metal 2 and joist 1 in the manner shown in Figures 7, 8 and 9. The upper corner portions of the side members 15 of the clip 3 are bent inwardly to form ears 16 upon which the nailing strip 4 is supported in a position somewhat spaced from the body member 10 of the clip. Adjacent the upper edges of the central portions of the side members 15 I form holes 17 adapted to receive nails 18 by means of which the nailing strips 4 are fixedly held in position upon the supporting ears 16.

No claim is made in this application to the particular assembly of connecting means for structural members, of which the holding member 9 is a part, the same being shown, described and claimed in my pending application Serial No. 79,530.

The steps of forming the floor and the use of the improvements herein described and shown in the accompanying drawings are then as follows: The joists of other main supports 1 are first positioned upon their end supports. The expanded metal 2 is then laid and secured by the usual ties to the supports 1 or, if the wedge 9 is utilized,

the clips 3 are positioned in the desired angular relation to the supports 1, and the wedges 9 driven down through the slots 11 and through the expanded metal 2 and wedged into the spaces between the bars 8, 70 thus also locking the broken or distorted ends of the expanded metal between the opposed faces of the bars 8 and the adjacent sides of the wedge 9. If the wedge 9 is not utilized, the clips 3 are secured by means of 75 ties 7. Then the nailing strips 4 are mounted upon the ears 16 and secured fixedly by the nails 18. Concrete 6 is then poured over and through the expanded metal and in and around the clips 3 and screeded 80 somewhat below the top surface of the nailing strips 4, as shown by space 20, Figures 6 and 10. After the concrete 6 has set, the floor 5 is laid and fastened by means of nails 19 to the strips 4, as shown in Figures 85 6 and 10.

What I claim is:

1. A clip for use in securing wood floors of fireproof floor construction, comprising a body member, and an angular side member 90 formed with means adapted to support a nailing strip a spaced distance from said body member, the clip being formed with means adapted for use in securing the same to the fire-proof base of the floor. 95

2. A clip for use in securing wood floors of fireproof floor construction, comprising a body member, and an angular side member formed with means adapted to support a nailing strip a spaced distance from said 100 body member and with means for use in securing said nailing strip, the clip being formed with means adapted for use in securing the same to the fire-proof base of the floor. 105

3. A clip for use in securing wood floors of fire-proof floor construction, comprising a base member, and an angular side member formed with means adapted to support a nailing strip, the base of the clip being 110 formed with a plurality of angularly disposed means adapted for use in securing the same to the fire-proof base of the floor in a selected position of a plurality of relatively angular positions. 115

4. A clip for use in securing wood floors of fire-proof floor construction, comprising a base member, and an angular side member formed with means adapted to support a nailing strip and means for use in securing said nailing strip, the clip being formed with means adapted for use in securing the same to the fire-proof base of the floor in a selective position of a plurality of relatively angular positions. 120

5. A clip for use in securing wood floors of fire-proof floor construction comprising a base member, and angular side members formed with inturned ears forming supports for nailing strips, and also formed with 130

means for use in securing said nailing strips, the clip being formed with means adapted for use in securing the same to the fire-proof base of the floor.

5 6. A stamped article for use in securing wood floors of fire-proof floor construction, comprising a base member formed with an elongated slot, an angular side member formed with nail holes adjacent its upper 10 free edge, and an inturned support for a nailing strip formed from said side member.

7. A stamped article for use in securing wood floors of fire-proof floor construction, comprising a base member formed with a 15 series of radially extending slots the inner parts of which merge into a common central hole, a pair of relatively right-angular side members formed with nail holes adjacent their upper free edges, and a pair of horizontally-aligned inturned supports for nailing strips formed from the upper side edge portions of each of said side members.

8. A stamped article for use in securing wood floors of fire-proof floor construction, comprising a base member formed with a series of radially extending slots the inner parts of which merge into a common central hole, a pair of relatively right-angular side members formed with nail holes adjacent 30 their upper free edges, the lower body portions of said side members being formed with comparatively large holes adapted to permit the flow therethrough of plastic material, and a pair of horizontally-aligned inturned 35 supports for nailing strips formed from the upper side edge portions of each of said side members.

9. Fire-proof floor construction comprising metal joists, expanded metal covering said joists, supports for wood-floor nailing strips mounted upon said expanded metal, means securing said supports in position upon said metal, nailing strips fastened to said supports a spaced distance from said metal, a plastic floor sub-base covering and 40 enveloping said expanded metal and supports, the upper surface of said sub-base lying substantially in the same horizontal plane as the upper surfaces of said nailing strips, and a wood floor laid upon said sub-base and secured to said nailing strips.

50 10. Fire-proof floor construction comprising metal joists formed with spaced members, expanded metal covering said spaced members, supports for wood-floor nailing strips mounted upon said expanded metal,

wedge-shaped resilient members intersecting the several supports and the expanded metal and fastened with a driving fit therein and to and between the spaced members of the joists, nailing strips fastened to said supports a spaced distance from said metal, a plastic floor sub-base covering and enveloping said expanded metal and supports, the upper surface of said sub-base lying substantially in the same horizontal plane as the upper surfaces of said nailing strips, and a wood floor laid upon said sub-base and secured to said nailing strips.

60 11. Fire-proof floor construction comprising metal joists formed with spaced members, expanded metal covering said spaced members, supports for wood-floor nailing strips mounted upon said expanded metal, said supports being provided with perforated base members, wedge-shaped resilient members intersecting the perforations of the several supports and fastened with a driving fit in said perforations and through said metal and to and between the spaced members of the joists, nailing strips fastened to said supports a spaced distance from said metal, a plastic floor sub-base covering and enveloping said expanded metal and supports, the upper surface of said sub-base lying substantially in the same horizontal plane as the upper surfaces of said nailing strips, and a wood floor mounted upon said sub-base and secured to said nailing strips.

70 12. Fire-proof floor construction comprising metal joists formed with upper horizontally-aligned spaced members, expanded metal covering said members, supports for wood-floor nailing strips mounted upon said expanded metal, said supports being provided with base members having elongated slots, wedge-shaped resilient members intersecting the slots of the several supports and fastened with a driving fit in said slot and through said metal and to and between the spaced members of the joists, nailing strips fastened to said supports adjacent the upper edges thereof, a plastic floor sub-base covering and enveloping said expanded metal and supports, the upper surface of said sub-base lying substantially in the same horizontal plane as the upper surfaces of said nailing strips, and a wood floor mounted upon said sub-base and secured to said nailing strips.

80 90 100 105 110
Signed by me this 1st day of December, 1925.

STANLEY MACOMBER.
